UNITED STATES PATENT OFFICE.

BENNO F. JANCKE, OF BROOKLYN, NEW YORK, ASSIGNOR TO TOWNSEND MANUFACTURING COMPANY, INC., OF NEW YORK, N. Y., A CORPORATION OF NEW YORK.

CURLER FOR PERMANENT WAVING OF HAIR.

Application filed March 2, 1928. Serial No. 258,642.

This invention relates to curlers used in permanent waving of hair, and provides improvements therein.

The invention provides a curler which 5 operates more reliably and effectively to produce a permanent wave in hair than prior types of curlers. The invention further provides a curler particularly effective in producing waves in young or new growth hair. 10 It further provides a curler of the character described which is of simple construction and which may be manufactured at moderate cost.

According to the present invention, the 15 curler is of a construction which acts under the influence of the heat used in waving, and during steaming, to stretch or to further stretch the hair wound thereon, and thereby more effectively aid in producing the alteration by which the wave is made.

A number of embodiments of the invention are illustrated in the accompanying drawing wherein—

Figures 1, 2 and 3 are respectively, two 25 views in elevation 90° apart and a cross-section on line III—III, Fig. 2, of one embodiment.

Figs. 4 and 5 are respectively, a view in 30 elevation and a cross-section on line V—V of a second embodiment, Fig. 4 being partly broken away to show parts in section.

Figs. 6 and 7 are respectively, a view in 35 elevation and in cross-section on line VII—VII of a third embodiment.

Fig. 8 is a cross-sectional view illustrating 40 a slight modification of the construction shown in Figs. 6 and 7.

Fig. 9 is a view partly in elevation and 45 partly in vertical section of a fourth embodiment; and

Figs. 10 and 11 are respectively, views of 50 a fifth embodiment, Fig. 10 being a view partly in elevation and partly in vertical section; Fig. 11 is a sectional view on an enlarged scale of the thermal-expansion element.

Fig. 12 illustrates a sixth embodiment, it being shown in longitudinal section.

Figure 13 is a cross-sectional view showing 55 the device in use.

Referring to said drawings, numeral 10 60 designates the curler as a whole. The curler is conveniently tapered toward its lower end, and also is conveniently round or approxi-

mately round in cross-section. A tress of hair is rather tightly wound around the 55 curler, and usually around the lower portion thereof indicated by the numeral 12. Moreover, the lower end of the curler, as indicated at 15, may if desired be provided with a narrow crotch, in which the piece of string 60 usually used for fastening the hair to the curler may be inserted. Any other suitable means for binding the tress of hair to the curler may be used.

According to the present invention, means 65 are provided for expanding under heat the curler or part thereof around which the tress of hair is wound, and thereby stretch or further stretch the wound hair. Thereby, when the curler is used in waving hair, and a 70 tress of hair is wound thereon, and subjected to steaming in the usual process of hair waving, there is a simultaneous stretching or additional stretching of the hair by reason of the expansion of the curler, and a better 75 and more effective wave thereby effected than without the use of the thermal expandible curler.

The expansion of the curler may be effected 80 by a great variety of means. The curler or the part thereof upon which the hair is wound, comprises an outer portion 14, and a thermal expandible part 16, adapted when heated, to expand or press the part 14 radially outward, and thereby stretch the tress of 85 wound hair. Conveniently, the part 14 is formed of metal, and part 16, also formed of metal, has a different degree of expansion under heat than the part 14. Furthermore, the curler preferably comprises longitudinal 90 portions which are movable independently, in order to facilitate the expansion of the device. The form of these independently movable portions may be various. In Figs. 1, 2, 3, 6, 7, 8 and 9, these are indicated by numerals 95 20, 21, while in Figs. 4, 5 and 10 these are indicated by numerals 20, 21, 22, 23.

As shown in Figs. 1, 2, 3 and 9, the curler is conveniently constructed in the form of a central strip 30 having at each side segments 100 composed of the strips 14 and 16, which are conveniently welded, brazed or otherwise secured together, and preferably secured at the outer end to the strip 30 by rivets, as indicated at 32. The strips 16, which are of metal, have a greater degree of expansion 105

under heat than the part 14. Consequently, when the curler is heated, the strips 14 and 16 expand unequally, and the strips buckle causing in this instance the lower ends to move or expand radially outward.

In Figs. 4 and 5 the curler is conveniently provided with a plurality, here shown as four, of independently movable longitudinal sections. The outer parts 14 are conveniently 10 formed of metal, and behind these and conveniently attached thereto are strips 16, the metal having a different degree of expansion under heat from the parts 14. These parts 14 and 16 are conveniently attached to a sleeve 36, by means of rivets or the like, as indicated at 38. When heat is applied, the strips 16 expand to a greater extent than the strips 14, and there is consequently a buckling and outward movement or expansion of the 20 lower ends, which has the effect of stretching the hair wound on the curler. In this embodiment the center or core is conveniently hollow, and a twisting rod 40 is provided therein. The lower end of the rod 40 projects at the lower end of the curler, and is provided with a narrow crotch 15 which receives and holds the string which is usually used to fasten the tress nearest the scalp to the curler. The opposite end of the rod 40 preferably projects at the outer end. When the rod 40 and the sleeve 36 are grasped, and the rod twisted, the tress of hair wound on the curler is tightened thereon. A ratchet 42 on the rod, inside of the sleeve, serves to 30 prevent back rotation of the rod 40.

In Figs. 6 and 7 there is shown another embodiment. In this embodiment the curler is conveniently formed of a composite solid rod consisting of the outer portion 14 and the inner portion 16 of metal having a different degree of expansion under heat than the part 14. The longitudinal portions 20, 21 are conveniently provided by slitting the said composite rod. This slit, as shown, may terminate short of the ends of the rod. When heat is applied, the part 16 expands to a greater extent than the part 14, buckling the said parts. This causes an expansion or radial outward movement along the length of the rod, which by reason of the tapered form of the rod is greater at the lower end than at the top. A modification of the form shown in Figs. 6 and 7 is shown in Fig. 8. Instead of making the curler as a solid rod, it may be composed of two tubes, the innermost, 16, having a greater degree of expansion under heat than the outer portion 14. It may be slit longitudinally in similar manner to the embodiment shown in Figs. 6 and 7.

60 In the embodiment illustrated in Fig. 9, the construction is generally the same as that shown in Figs. 1, 2 and 3. There is, however, incorporated additional means 50 adapted to operate to hold the expansible portions in expanded position, so as to remain in the po-

sition to which they have been expanded after the heat has been removed. This means conveniently comprise a wedge 51 adapted to be moved as or when the expansible portions move outwardly, and thereby prevent them from receding as the device cools. To this end, the wedge 51 may be conveniently connected to a rod 54 running through the middle of the curler, and having a light spring 56 adapted to move the wedge in the direction of its point, when it is free to move by reason of the expansion or outward movement of the portions 20, 21 of the curler. The rod 50 may conveniently extend beyond the outer end of the curler, in order that it may be pressed so as to push the wedge back to allow the portions 20, 21 to move inward after they are cool and it is desired to restore the parts to normal position.

In Figs. 10 and 11, in which another embodiment is illustrated, the curler is conveniently formed of a plain tube, this tube also conveniently being slit to provide a plurality of independently movable longitudinal sections 20, 21, 22, 23. Inside of this tube there is placed a spiral strip 60. The strip 60 is conveniently composed of two metals, one of which has a greater degree of expansion than the other. One end of this spiral strip 60 is attached to the curler, as by means of rivets 62. When the spiral strip 60 is subjected to heat, the differential expansion of its two parts causes it to buckle and to uncoil. The uncoiling broadens the diameter of the coil, and consequently spreads the expansible portions of the curler, as for example the longitudinal portions 20, 21, 22, 23.

105 In Fig. 12 there is illustrated a further embodiment. In this embodiment the curler comprises a tube 12 preferably of metal having a relatively high coefficient of expansion, and is also preferably made very thin so as to be capable of expansion, or it may be slotted if desired. Numeral 16 designates the means for expanding the tube 12, and is conveniently composed of a rod or tube inside of and attached in suitable manner to the ends or spaced portions of the tube 12 and has a lower coefficient of expansion than the tube 12. Tube 16 is conveniently made of invar 110 steel.

115 In waving young hair, or that part nearest the scalp, which is the latest growth, it is desirable to give these portions a greater stretch than the other portions of the hair, due to the greater elasticity of the new hair. This is provided for by the present invention.

120 In Fig. 13 the device is shown in use. A strand of hair is wound on the curler 10 as shown at y. Around this is placed a wrapper or envelope 75 enclosing a moistened absorbent such as a piece of blotting paper 77. Over the wrapper 75 is placed a heater containing the heating wire 80. The heat from the heater causes the moisture in the ab-

sorbent 77 to steam, heating hair and also the curler 10, causing it to function as hereinbefore described.

The heater shown is claimed in my application Serial No. 230,339, filed November 1, 1927. Any other form of heater may be used.

The invention may receive various other embodiments than those herein specifically illustrated and described.

10 What is claimed is:—

1. A curler for permanent hair waving around which a tress of hair is adapted to be wound, and means expansible under heat adapted to expand said curler to stretch or to further stretch the hair wound on said curler.

2. A curler for permanent hair waving around which a tress of hair is adapted to be wound, and means expansible under heat adapted to expand said curler to stretch or to further stretch the hair wound on said curler, said curler comprising longitudinal portions capable of independent movement.

3. A curler for permanent hair waving around which a tress of hair is adapted to be wound, and means expansible under heat adapted to expand said curler to stretch or to further stretch the hair wound on said curler, and means adapted to hold said curler in expanded position.

4. A curler for permanent hair waving around which a tress of hair is adapted to be wound, and means expansible under heat adapted to expand said curler to stretch or to further stretch the hair wound on said curler, said curler further comprising means rotatable therein to which one end of a tress of hair is adapted to be fastened, and adapted to be turned to tighten the winds of hair on said curler.

5. A curler for permanent hair waving comprising a part around which a tress of hair is adapted to be wound, and a part having a greater degree of expansion under heat than said part on which said hair is wound adapted to radially extend said latter part.

6. A curler for permanent hair waving, around which a tress of hair is adapted to be wound, of metals of different degrees of expansion, adapted under the influence of heat to bulge said curler outwardly and expand the tress of hair wound thereon.

7. A curler for permanent hair waving, according to the preceding claim, comprising longitudinal independently movable portions.

In witness whereof, I have hereunto signed my name.

BENNO F. JANCKE.
